UNITED STATES PATENT OFFICE.

FRANK BERRY, OF YAKIMA, WASHINGTON.

TENT FRAME.

Application filed June 18, 1924. Serial No. 720,820.

This invention relates to a supporting frame for palmetto tents and it has for its object to provide a simple inexpensive and efficient structure adapted to be collapsed and brought to small compass when it is to be carried and serving when opened out to support the material of the tent in distended condition without the necessity of employing a central pole.

Further objects and advantages of the invention will be set forth in the detailed description which follows. In the accompanying drawings:

Figure 1 is a perspective view of the frame of the invention in collapsed condition,

Figure 2 is a perspective view of the frame of the invention in opened or distended position, and

Figure 3 is a sectional view of the central clamps hereinafter described.

Like numerals designate corresponding parts in all of the figures of the drawings.

The device in the present invention comprises a central spider like clamp consisting of the upper half 5 to which the inner ends of radial rods 6 are secured, and a lower half 7 which may be moved away from the half 5 to permit the rods 6 to be swung upon their attaching pivots 5^a to the collapsed position illustrated in Fig. 1, it being understood that at this time the lower part of the clamp is turned until its legs lie out of alignment with the legs of the upper part of the clamp.

When the two halves of the clamp are brought together and the lower half is secured against movement with respect to the upper half, it will be clear that the rods 6 will be secured in their radial relation to the clamp. The other ends of the radial rods 6 are pivotally connected as at 9 to cup like members 10, said cup like members carrying the legs or poles 11 by which the tent as a whole is supported. The cup members 10 are shaped to fit into the four corners of the tent. A cup 12 upon a vertical rod 13 is adapted to fit into the peak of the tent and this rod may be adjusted vertically with respect to the clamp 5. When the rod 13 is thrust upwardly it is manifest that the material of the tent will be placed under tension and that there will be a tendency to draw the four corners of the tent into firm engagement with the cup 10.

The rod 13 is slidably mounted in a tubular section 14 the upper end of which is

screwed into the upper half 5 of the clamp, and the lower half 7 of the clamp is movable on this tubular section and is adapted to be bound upon said tubular section and 60 against the lower face of the upper half of the clamp by means of a screw 15 this screw being carried by a movable collar 16^a located below the lower face of the bottom half of the clamp. A chain 16 connected 65 to the collar 16^a carries a pin 17 which is adapted to pass through an opening 18 formed in the tubular section 14 and through any one of the series of openings 19 formed in the vertical rod 13. 70

Thus, when the tent is to be erected the rods are first brought to their radial position and then the bottom half of the clamp is pressed upwardly against the lower face of the upper half of the clamp and the screw 75 15 is tightened to bind it in this position.

Then the cups 10 are fitted into the four corners of the tent, the cup 12 is fitted into the peak of the tent, and the rod 13 is forced upwardly until the material of the tent is 80 placed under the desired tension, after which the pin 17 is inserted in the hole 19 which is most convenient and comes nearest to aligning with the hole 18.

The reverse operation takes place when 85 the tent is to be lowered.

From the foregoing description, it will be seen that simple and efficient means are herein provided for carrying out the objects of the invention. However, it is to be understood that this invention is not limited to the precise construction set forth but that it includes within its purview whatever changes fairly come within either the terms or the spirit of the appended claims. 95

Having described my invention, what I claim is:

1. A device of the character described comprising a two part spider like clamp the upper half of which has a plurality of 100 radial arms pivotally connected thereto, upright legs pivotally connected to the outer ends of the radial arms, means for binding the lower half of the clamp against movement with relation to the upper half, and 105 a vertically adjustable tent top supporting rod movable through said clamp.

2. A device of the character described comprising a two part spider like clamp, a tubular element screwed into the upper half 110 of the clamp and upon which the lower half of the clamp slides, a means for bind-

ing the lower half of the clamp upon said tubular element, a vertically adjustable tent top supporting rod movable through said tubular element, and means for binding said rod against movement with respect to said tubular element, a plurality of radial arms pivoted to one part of the clamp and engaged by the other part of said clamp to be thereby held against movement and a plurality of upright legs pivotally connected to the outer ends of said arms.

3. A device of the character described comprising a two part spider like clamp, the confronting faces of which are complementally channeled, a plurality of radial arms pivotally mounted in the channeled portions of the upper part of the clamp and being held against movement out of said channeled portions by the lower part of the

clamp when the two parts of the clamp are 20 brought together face to face, a tubular member carried by the upper part of the clamp and upon which the lower part of the clamp slides, said tubular member being traversed by a transverse opening, a tent 25 top supporting rod mounted to slide in said tubular member, said rod having a plurality of transverse openings formed therein and a pin adapted to pass through the opening of the tubular member and any one of the openings of the rod to hold said rod in varying 30 position of vertical adjustment with respect to the clamp, and upright legs pivotally connected to the outer ends of the radial arms.

In testimony whereof he affixes his signature.

FRANK BERRY.
